UNITED STATES PATENT OFFICE.

JOSEPH M. FREDERICK, OF BALTIMORE, MARYLAND, ASSIGNOR TO POMPEIAN ROMANZA CORPORATION, OF BALTIMORE, MARYLAND.

CAN-CAPPING MACHINE.

Application filed January 26, 1923. Serial No. 615,029.

To all whom it may concern:

Be it known that I, JOSEPH M. FREDERICK, citizen of the United States, residing at Baltimore, in the State of Maryland, have invented certain new and useful Improvements in Can-Capping Machines, of which the following is a specification.

This invention relates to can capping machines, and more particularly to machines for crimping to a flanged opening in the can a correspondingly flanged cap.

Hitherto the cap used to retain the contents in the can and to exclude the atmosphere therefrom was soldered to the flange or upright shoulder of the opening in one face of the can. This process of soldering proved expensive and impracticable in that it required two or three operations for the accomplishment of this object, which greatly added to the cost. One of the objects of my invention is, therefore, to provide a can closing or capping mechanism of simple and more practical construction which produces in operation an air-tight joint and one which positively retains the contents of the can in a pure condition and unaffected by atmosphere.

A further object is to provide a capping machine which will crimp a cap to a can without the use of solder, chemicals and the like.

A further object is to provide a can capping mechanism by which the cap is crimped to the can in one operation and with the least possible expense.

A further object is to provide a simple, economical and labor-saving device to accomplish the above results in an efficient and practical manner.

The invention accordingly consists in the features of construction, the combination of parts, and in the unique relation of the various members and the relative proportioning and dispositioning thereof, all as more clearly outlined herein.

To enable others skilled in the art to fully comprehend the underlying features thereof in order that they may embody the same, by numerous modifications in structure and relation contemplated by this invention, drawings depicting a preferred form of the invention have been annexed as part of this disclosure and in such drawings like characters of reference indicate corresponding parts throughout all the views, of which—

Figure 1 is a perspective view of the major parts of an assembled cap crimping machine;

Figure 2 is a view in elevation, partly in section, of the power transmitting device and crimping mechanism;

Figures 3, 4 and 5 are detail views showing the crimping mechanism per se in different stages of its operation.

Referring now to the drawings in detail, and more particularly to Figure 1, a standard 5 is positioned in a base 6, which is of the usual form, the same being provided with holes for the reception of bolts or other fastening means by which the base 7 may be secured to the floor. The standard 5 is provided with supporting means, such as brackets 7, 8 and 10, which are firmly held in adjusted position by set screws or the like. The supporting bracket 8 carries a short shaft 11 which is provided at one end with a power transmitting and reducing means, such as a worm 12. Positioned in the brackets 7 and 8 is a stationary shaft 13, the same being flared outwardly at its lower extremity, as at 14. The worm 12 meshes with a gear 15 which, as is seen from Figure 2, is keyed at 16 to a cooperating sleeve 17 which rotates about the shaft 13 with said gear, and which is provided with a suitable bushing 18 in the bracket 8. A crimping head 19 is provided at its upper extremity with an upstanding tubular portion 20, preferably sweated to the sleeve 17 upon its inner face and has a bushing 21 of brass or other desirable metal held to its outer face in a similar manner. Suitable bearings are provided as at 22 and a fiber washer 23 reduces friction between the stationary and rotating members.

The shaft 13 may be held against rotation in the bracket 7 by fastening means, such as a set screw, but is permitted a slight longitudinal motion, such movement being limited by a spring and collar 24. Surrounding the bushing 21 is a sleeve 25 which is adapted to slip or move relatively on the outer face of this bushing and the lower portion of the adjacent bracket 8. The bushing 25 at its lower extremity is beveled as at 26 for the purpose hereinafter mentioned.

Pivoted to the standard 5 is an operating handle 27 held to the bushing 25 by a pin 28 operating in a slot 30. To insure auto-

matic return, the operating handle is resiliently held normally in its uppermost position by suitable means, such as a bracket 31, stud 32, spring 33 and locking nuts 39.

5 The rotating head 19, previously referred to, is provided on one side with a slot or recess 34 in which is mounted a movable crimping arm 35. This crimping arm 35 is pivoted as at 36, and by means of a resiliently mounted screw 37 engaging a stud 38, the crimping arm 35, as will be seen, is permitted a resilient pivotal movement, as well as being normally held in retracted position. On the opposite side of the head 13 19 is positioned a weight 29 by which the inertia of the rotating members is balanced.

In the upper portion of the crimping arm is mounted a beveled wheel 40, which, by its association with the beveled portion 26 20 of the collar 25, constitutes a co-acting cam relation. At the lower extremity of this crimping arm 35 is a crimping wheel 41 beveled as at 42 to provide a crimping action with the flaring portion 14. It will 25 thus be seen that by a downward movement of the operating handle 27, carrying with it the collar 25, the beveled portion 26 of the same will engage with the wheel 40 and thereby swing the crimping arm 35 about its pivotal center 36 to carry inwardly the wheel 41 into close proximity to the outwardly flared portion 14 of the shaft 13.

As shown in Figures 3, 4 and 5 the crimping wheel 41 is so arranged in the arm 35 that when brought into proximity with the flaring portion 14 for crimping action the beveled face is slightly off the vertical, whereby the crimping action is effected along the line of the lower and outermost portion of the beveled face to effect a substantial line contact crimping action between the crimping wheel and the flared shaft. Thereby a crimping action is produced only at the lower portions of the flared shaft and the crimping wheel as defined by the term, "substantial line contact."

Mounted in the base 6 is a movable table 43 which may be raised by operation of a foot lever 44 and a connecting link motion. 50 In order to insure against rotation of the said movable table, guide fingers 45 are provided in the table 43, said guide fingers embracing the standard 5. The bracket 10 has a V-shaped portion 46, in the present construction, against which the cans, 55 rectangular in cross-section, may be held. A different support would, of course, be used with cans of different form.

Power may be transmitted to the mechanism from any suitable source of power, for example, by a pulley 47, associated with the shaft 11.

Adjustments permitting the crimping of various thicknesses of caps is provided in 65 the following manner: By screwing or un-

screwing the locking nuts 39 the downward throw of the operating handle 27 is limited, and the consequent reciprocation of the collar 25 controlling the swing of the crimping arm 35 through the coating cam surfaces 25 and 26 results in the establishment of a greater or less distance between the wheel 41 and the flared portion 14. Various depths of cans may also be taken care of by raising or lowering the shaft 13 by adjustment of the fastening means in the bracket 7.

The operation of the machine is substantially as follows:

A can, designated by the numeral 50, is 80 placed upon the table 43 and a flanged cap 51 loosely positioned upon a flanged opening 52 in the top face of the can, see Figure 3. By movement of the foot lever 44 the can is raised, the same being guided by the V-shaped arm 46, to the position in which the flared portion 14 of the shaft 13 fits into the cap 51, the shaft at this point resiliently holding the cap and can with the necessary degree of firmness, (Figure 4). Power is transmitted through the worm and gear 12 and 15, the sleeve 17 to the head 19, and the crimping arm 35, carrying the crimping wheel 41, receives a resulting rotation. Upon downward movement of the hand lever 27 the crimping wheel 41 approaches the flanged cap, as shown in Figure 5, and, revolving about the stationary flaring portion 14 of the shaft 13, tightly crimps the cap 51 to the flanged portion 53 of the opening 52. It will be noted at this point that the crimping action takes place between the lower portion of the bevel 42 of the wheel 41 and the bottom portion of the flaring end 14 of the shaft 13.

This machine has proved highly efficient in use and operation and provides a positive air-tight seam. It has been found by experiment that although the side or bottom seams of the can may rupture, the seam formed by this machine has been retained in perfect condition.

It is thus seen that the present invention provides a simple and practical mechanism adapted to accomplish, among others, all of the objects and advantages herein stated.

Without further analysis the foregoing will so fully reveal the gist of this invention that others can, by applying current knowledge, readily adapt it for various applications without omitting certain features that from the standpoint of the prior art fairly constitute essential characteristics of the generic or specific aspects of this invention and, therefore, such adaptations should and are intended to be comprehended within the meaning and range of equivalency of the following claims.

I claim:

1. In a can capping machine of the character described, in combination, a standard, a crimping device comprising brackets mounted on said standard, a non-rotatable shaft 5 mounted in said brackets and having a flaring portion at the end thereof, a sleeve enveloping said shaft for a portion of its length, means whereby said sleeve is rotated, a rotatable head rigidly associated 10 with said sleeve, a crimping arm resiliently pivoted in said rotatable head, a crimping wheel mounted in said crimping arm, means adapted to bring said crimping wheel into close proximity with said flaring portion of 15 said shaft, said means comprising a collar having a beveled portion at the end thereof, an operating handle pivoted to said standard and associated with said collar, and a wheel mounted on said crimping arm and 20 adapted to co-act with said beveled portion of said collar, a table adapted to be upwardly moved, and means associated with one of said brackets holding a can in operative position, said non-rotatable shaft being resiliently mounted thereby to hold the 25 can with the necessary degree of firmness.
2. In a can capping machine of the character described, in combination, a standard, a crimping device comprising brackets mounted on said standard, a non-rotatable shaft resiliently mounted in said brackets and having a flaring portion at the end thereof, a sleeve enveloping said shaft for a portion of its length, means whereby said sleeve is rotated, a rotatable head rigidly associated 30 with said sleeve, a crimping arm resiliently pivoted in said rotatable head, a crimping wheel mounted in said crimping arm, manually operable means adapted to bring said crimping wheel into close proximity with 35 said flaring portion of said shaft to effect a substantial line-contact crimping action therebetween, a longitudinally movable support adapted to raise a can in operative crimping position, and means associated with one of said brackets to maintain the can in said operative crimping position.
3. In a can capping machine of the character described, in combination, a standard, a crimping device carried by brackets mounted on said standard, said crimping device comprising a non-rotatable shaft resiliently mounted in said brackets, and having a flaring portion at the end thereof, a sleeve enveloping said shaft for a portion of its length, means whereby said sleeve is rotated, a rotatable head having an annular 40 standing portion surrounding said sleeve and fixed thereto and adapted to be rotated thereby, said head having a longitudinal recess therein, a crimping arm resiliently pivoted in said recess, a single crimping wheel mounted in said crimping arm, manually operable means adapted to pivot said crimping arm thereby to bring said crimping wheel into close proximity with said flaring portion of said shaft to effect a substantial line-contact crimping action therebetween, a longitudinally movable support adapted to raise a can in operative crimping position, and means associated with one of said brackets to maintain the can in said operative crimping position.

In witness whereof I have hereunto set my hand and seal this 12th day of January, 1923.

JOSEPH M. FREDERICK. [L.S.]

Witness:
